UNITED STATES PATENT OFFICE.

JAMES CAVANAGH, OF BOSTON, MASSACHUSETTS, ASSIGNOR TO UNITED SHOE MACHINERY COMPANY, OF PATERSON, NEW JERSEY, A CORPORATION OF NEW JERSEY.

METHOD OF MAKING SHOES.

1,163,596.

Specification of Letters Patent.

Patented Dec. 7, 1915.

Original application filed November 22, 1912, Serial No. 732,971. Divided and this application filed September 17, 1914. Serial No. 862,211.

To all whom it may concern:

Be it known that I, JAMES CAVANAGH, a citizen of the United States, residing at Boston, in the county of Suffolk and State of Massachusetts, have invented certain Improvements in Methods of Making Shoes, of which the following description, in connection with the accompanying drawings, is a specification, like reference characters on the drawings indicating like parts in the several figures.

This invention relates to methods of making shoes, and in particular to a method for use in lasting and fastening shoe uppers to 15 welt shoe innersoles or to turn shoe soles.

In lasting welt, or turn, shoes by hand or on machines of the "hand method" type an example of which is disclosed in United States Letters Patent No. 584,744, dated 20 June 15, 1897, the upper is stretched over the last by pincers progressively, or one section after another, and the successively stretched portions of its margin are placed against the lip or rib of the innersole or sole 25 and secured thereto by lasting tacks. These tacks, whether driven by hand or machinery, lie substantially perpendicular to the plane of the shoe bottom, and are usually driven fairly close together so as to hold the 30 upper securely in position about the last. When allowed to remain during the subsequent operation of permanently uniting the upper and welt to the innersole by the stitches of the inseaming machine these tacks 35 offer an obstruction to the movements of the needle and awl which frequently encounter the tacks and are bent or broken. In order to obviate this objection to the use of lasting tacks, under one practice the shoes have been 40 allowed to remain in lasted condition a considerable length of time until the upper has become set to the contour of the last. The lasting tacks are then withdrawn, and a lesser number of "stay" tacks are driven 45 through the upper to hold it in position temporarily, during the inseaming operation. While this practice reduced, to some extent, the difficulty above referred to it failed to prevent an occasional breakage of the awl 50 and needle of the inseaming machine as, while the stay tacks were less in number than the lasting tacks, they were also driven perpendicular to the plane of the shoe bottom, and hence lay directly in the path of

the needle and awl as they passed through 55 the between substance in a substantially horizontal direction.

The present method has for one of its principal objects the entire elimination of lasting tacks as a securing means for the successively stretched and overworked sections of upper in hand method lasting, whereby the objections to such tacks, or to any like fastenings for the upper sections that extend in the path of movement of the awl and 65 needle, are obviated.

With such object in view this method includes the driving of independent fastenings through the upper sections and the lip of the innersole in a direction substantially 70 parallel with the last bottom as said sections are worked successively into lasted position. These fastenings not only act transversely of the lip, but are located above the path usually traversed by the awl and needle, and 75 hence offer no obstruction to the operation of said elements. While the method, in its broadest aspect, contemplates applying fastenings of any appropriate character transversely of the lip to secure the successively 80 overworked upper sections thereto, it is preferred to use for this purpose staples of fine wire whose ends are clenched upon the inner side of the lip of the innersole. These particular fastenings offer practically no obstruction to the awl and needle, but nevertheless may be made sufficiently strong to effectively secure the upper under lasting tension to the lip of the innersole if inserted 85 progressively as the lasting is performed 90 step by step along the sides of the shoe and to hold the upper in such position until the completion of the inseaming operation.

This method may be practised by the hands of a shoemaker with the aid of such 95 simple tool as are well known to workers in this art, or it may be very effectually practised by aid of machinery comprising upper stretching grippers of the hand method lasting machine type and staple fastening mechanism such, for example, as proposed by Drey in United States Letters Patent No. 1,011,592, which grippers and stapling mechanism have been organized into a machine, which is described and claimed in pending 100 application, Serial No. 623,860, filed April 28, 1911, for the purpose of practising my invention. Other machines designed for use

in practising this invention are shewn in co-pending applications, Serial No. 563,431, filed October 5, 1910 and No. 732,971, filed November 22, 1912, of which latter application this present application is a division.

- In the drawings, Figure 1 is a plan view of the forepart of a pulled-over shoe to be lasted. Fig. 2 shows the shoe partially lasted by repeated operations which include the stretching of the upper over a last and forcing each overworked portion of the upper into the angle formed by the feather edge and lip of a welt shoe innersole and securing each overworked portion of the upper in position by an independent fastening staple that is driven through the upper and lip in a direction transverse to the lip and in a plane above the location for the inseam stitches and is clenched on the inside of the lip. Fig. 3 is a transverse section through the shoe showing on the right hand side of the shoe the lasting and fastening operation as it may be practised in accordance with this invention. Fig. 4 shows a bottom plan view of a shoe lasted in accordance with this invention.

In carrying out this method, the operator takes a last having thereon the usual shoe materials that are assembled on the last and pulled over prior to the lasting operations, said materials including an innersole provided with a lip 2 for a welt shoe or a sole provided with a shoulder for a turn shoe, stretches successive sections of the upper, and lays the marginal portion of each section over upon the innersole or sole and forces it into the angle formed by the feather edge 3 and said lip or shoulder. As each section of the upper is thus worked into lasted position, a fastening 4 is driven through the upper and lip substantially parallel with the plane of the innersole or sole and at a sufficient distance thereabove to be out of the path of movement of the awl and needle 6 of the inseam sewing machine. The upper sections are thus secured reliably as the lasting progresses, and by fastenings that are so placed that they draw the margin of the upper snugly up to and against the lip or shoulder, and maintain it in the position in which it is subsequently permanently attached by the inseam stitches. A preferred form of fastening for use in carrying out the method is a staple of fine wire, as it has been found that these, when driven through the upper and lip in step-by-step lasting and substantially parallel with the last bottom and with their ends clenched on the inside of the lip, practically eliminate all danger of being encumbered by the sewing instrumentalities, and at the same time act to hold the upper securely in lasted position. In practising this method the operator may begin at the shank of the shoe, and work first along one side, then around

the toe and along the other side of the shank, driving a staple through the upper and lip, as each section of upper is lasted and clenching the staple, as against the clenching work rest 12. Where, however, it is desired to secure the upper at the toe by a toe binder, as shown in Fig. 4, one side of the shoe will first be lasted step-by-step, and a staple driven through each successively overworked upper section, from the shank on one side of the shoe to a point at or near the toe tip line. The driving of staples will then be suspended and a continuous binder 9 will be applied about the toe to bind in the lasted upper, the ends of the binder being anchored to one or both of the usual pulling-over tacks, or it might be anchored by a staple. The remaining sections of the upper from the end of the binder to the shank on the other side of the shoe will then be successively fastened in position, as they are overworked, by the independently applied staple-like fastenings.

The shoe may, if desired, be lasted by pulling the successive upper sections by hand pincers, and driving the fastenings through each upper section and the lip by a hand-operated tool, and the toe binding operation may also be performed by hand. I prefer, however, to practise this invention with the aid of an organized machine, and have shown in the drawings grippers 8 and a stapling mechanism 10 of such a machine.

It will be seen that an important step in the present method consists in inserting single fastenings during the overworking operation, as each successive section of the upper is stretched over the sole margin, said fastenings being of a character and driven in a direction relative to the shoe bottom that will permit such fastenings to be used as the initial, and final, steering means for holding the upper in lasted condition until the inseamming machine permanently unites the upper, welt and innersole. As these fastenings lie above and parallel with the plane of movement of the awl and needle of the inseamming machine, they are not in a position to be struck by these elements, as is the case with the usual lasting tacks, or stay tacks, which are driven substantially perpendicular to the plane of the sole, and hence offer a substantial obstruction to the sewing operation.

Having thus described my invention and explained how it may be practised, I claim as new and desire to secure by Letters Patent of the United States:—

1. That improvement in methods of making shoes which consists in working an upper over a last by repeated operations and forcing each overworked portion of the upper into the angle formed by the feather edge and lip of an innersole and securing each overworked portion of the upper in

position by an independent fastening that is inserted through the upper and lip in a direction transverse to the lip, the overworking, forcing and securing being carried out 5 successively relative to each other and progressively along first one side of the shoe and then along the other side.

2. That improvement in methods of making welt shoes which consists in lasting a 10 shoe step by step by repeated operations applied progressively to successive portions of the shoe and fastening each portion in position as it is lasted by a separate metallic fastening inserted in a direction substantially parallel with the shoe bottom through the upper and through the lip of a welt shoe 15 innersole and clenched to secure it in upper fastening position.

3. That improvement in methods of making welt shoes which consists in lasting a 20 shoe step by step by repeated operations applied progressively to successive portions of the shoe and fastening each portion in position as it is lasted by a separate metallic fastening inserted in a direction substantially parallel with the shoe bottom through the upper and through the lip of a welt shoe 25 innersole and clenched to secure it in upper fastening position, said fastenings being located in a plane above the location for the 30 inseam stitches, and then sewing the inseam below the plane of said fastenings and thereby tightening the lasted upper by drawing it into the angle between the said lip and the 35 feather of the innersole.

4. A method for use in the manufacture of shoes, comprising working successive portions of an upper over a last by repeated operations, forcing each section of upper as it 40 is overworked into the angle formed by the lip and feather edge of an innersole, driving a staple through each section of the upper while it is held in said angle, and clenching the ends of the staple on the inside of the 45 lip.

5. A method for use in the manufacture

of shoes, comprising working successive portions of an upper over a last by repeated operations, driving a staple through each overworked section of the upper and the lip of 50 an innersole in a direction transverse to the lip, and clenching the ends of each staple on the inside of the lip.

6. A method for use in the manufacture of shoes, comprising working successive portions of an upper over a last by repeated operations and securing each portion of the upper as it is overworked to the lip of an 55 innersole by driving a staple through the upper and lip in a direction transverse to 60 the lip.

7. A method for use in the manufacture of shoes, comprising working an upper over a last by repeated operations, and driving through each section of the upper as it is 65 overworked and through the lip of an innersole a separate fastening which lies above the line in which the inseam stitches are to be inserted.

8. A method for use in the manufacture of shoes, comprising pulling an upper to a last and laying it over upon an innersole provided with a lip by repeated operations, and inserting a separate fastening through 70 each section of the upper as it is overworked 75 and through the lip in a direction substantially parallel with the shoe bottom.

9. A method for use in the manufacture of shoes, comprising working an upper by 80 repeated operations over a last having thereon an innersole provided with a lip, and inserting an individual fastening through each portion of the upper as it is overworked and through the lip transversely of the lip to secure the upper in position.

In testimony whereof I have signed my name to this specification in the presence of two subscribing witnesses.
